CLAIM

The ornamental design for a trimmer spool non-radial straight channel, as shown and described.

DESCRIPTION

FIG. 1 is a top front left perspective view of a first embodiment of a trimmer spool non-radial straight channel in accordance with my design;

FIG. 2 is a top back right perspective view of the trimmer spool non-radial straight channel of FIG. 1;

FIG. 3 is a front elevation view of the trimmer spool non-radial straight channel of FIG. 1;

FIG. 4 is a back elevation view of the trimmer spool non-radial straight channel of FIG. 1; and

FIG. 5 is a top view of the trimmer spool non-radial straight channel of FIG. 1, rotated through ninety degrees;

FIG. 6 is an enlargement of the highlighted region, taken along line 6, of FIG. 3;

FIG. 7 is an enlargement of the highlighted region, taken along line 7, of FIG. 4; and

FIG. 8 is a cross-section of the trimmer spool non-radial straight channel taken along line 8-8 of FIG. 3, rotated through ninety degrees;

FIG. 9 is a top front left perspective view of a second embodiment of a trimmer spool non-radial straight channel in accordance with my design;

FIG. 10 is a top back right perspective view of the trimmer spool non-radial straight channel of FIG. 9;

FIG. 11 is a front elevation view of the trimmer spool non-radial straight channel of FIG. 9;

FIG. 12 is a back elevation view of the trimmer spool non-radial straight non-radial channel of FIG. 9; and

FIG. 13 is a top view of the trimmer spool non-radial straight channel of FIG. 9, rotated through ninety degrees;

FIG. 14 is an enlargement of the highlighted region, taken along line 14, of FIG. 11;

FIG. 15 is an enlargement of the highlighted region, taken along line 15, of FIG. 12; and,

FIG. 16 is a cross-section of the trimmer spool non-radial straight non-radial channel taken along line 16-16 of FIG. 11, rotated through ninety degrees.

The broken lines illustrate portions of the environment that form no part of the claimed design.
